(57) **CLAIM**

The ornamental design for a gazebo canopy, as shown and described.

DESCRIPTION

FIG. 1 is a front, right and top perspective view of a gazebo canopy, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 of FIG. 1 thereof; and,

FIG. 10 is an enlarged view of portion 10 of FIG. 2 thereof. The broken lines depict portions of the gazebo canopy that form no part of the claimed design.

1 Claim, 10 Drawing Sheets
